(57) **CLAIM**

The ornamental design for a push-up board, as shown and described.

DESCRIPTION

FIG. 1 is a top, front and right side perspective view of a push-up board showing my new design; FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof showing the push-up board in an alternative folded position;

FIG. 10 is a perspective view thereof showing the push-up board with surface decoration; and,

FIG. 11 is a perspective view thereof showing one of the push-up board's use environments where handles are inserted.

All broken lines in all figures are included for the purpose of illustrating environment and unclaimed features of the design and form no part of the claimed design.

1 Claim, 11 Drawing Sheets
